UNITED STATES PATENT OFFICE.

WILLIAM FREDRICK DE KONATH, OF REVERE, MASSACHUSETTS.

SAFETY-RAZOR.

1,146,769.

Specification of Letters Patent. Patented July 13, 1915.

Application filed June 24, 1914. Serial No. 847,102.

To all whom it may concern:

Be it known that I, WILLIAM FREDRICK DE KONATH, a citizen of the United States, and resident of Revere, in the county of Suffolk and State of Massachusetts, have invented new and useful Improvements in Safety-Razors, of which the following is a specification.

This invention relates to safety razors, and its object is to provide a razor of novel and improved construction, whose blade may be stropped or honed without removing it from the razor frame, by merely freeing the blade from its guard and clamping member and running an actuating roller over the strop or hone.

In the accompanying drawings which illustrate one embodiment of the invention,—Figure 1 is a side view, partly in longitudinal section, showing the razor with the parts in position for stropping or honing; Fig. 2 is a plan view of the razor with its parts in the position shown in Fig. 1 and with the handle broken away; Fig. 3 is a front view with the parts in the same position; Fig. 4 is a plan view, partly in section, of the clamping member; Fig. 5 is a front view of said clamping member; Fig. 6 is a longitudinal sectional view, with the handle broken away, showing the parts assembled and in position for use; and Fig. 7 is a detail sectional view of the outer end of the handle.

Referring to the drawings, A represents a forked frame, and B is a hollow handle rotatably connected to the fork. A rotatable shaft C extends between the two branches of the fork A, and is journaled therein near the ends of the arms of the fork. At the ends of shaft C are the pinions c, lodged within suitable recesses in the arm of the fork, and meshing with pinions d at the ends of roller D. The roller D is journaled at the outer ends of the arms of the fork, and its periphery projects beyond the extremity of the forked frame, in the clear, for the purpose hereinafter explained.

E is a blade-holder comprising a pair of jaws which grip the base of the blade F. Said jaws are grooved as shown at e, e, to receive the bead or head f which extends

across the base of the blade. The blade-holder E is mounted on shaft C by means of a sleeve e' which permits the shaft to turn relatively to the blade-holder, but the blade-holder is frictionally connected to the shaft by sleeve sections e'', held in position by screws e''' by which the frictional engagement of the sleeve sections may be varied. The blade F may be removed from the blade-holder by sliding the head f endwise out of the grooves e.

A guard G, having an extensible section g, engages the inner side of the blade F and constitutes one of the two clamping members which support and hold the blade in position for use. The guard G is provided at its ends with a pair of lugs g', g', which slide in guide ways a, a, formed in the inner sides of the arms of forked frame A; and a screw shaft H connected at its end with guard G, and extending into the hollow handle B, moves the guard G forward and backward. Said screw shaft is moved endwise by turning the handle B, which is inferiorly threaded and co-operates with the thread h on shaft H. In order to adjust the extensible guard section g relatively to the edge of the blade, the guard section g is made with two end-arms g'' which are slidably secured to guard G, and may be held in adjusted position by screws g''' entering the ends of the guard G.

A detachable clamping member J engages the outer side of the blade F and co-operates with the guard to hold the blade in position for use. The clamping member J is provided at each end with an inwardly turned lip or flange j forming a channel into which fits an upwardly extending lug or finger a'' on the forked frame. On the lower edge of the clamp J are ears j' having beveled ends fitting the under cut shoulders a''' on the frame A. The clamp J is held in position against the outer side of the blade F by the pressure exerted by the guard G when the latter is screwed forward into operative position.

When the razor is ready for use the parts are in the position shown in Fig. 6, with the blade F clamped between the movable guard G and the detachable clamp member J.

When it is desired to strop or hone the blade, the guard G is withdrawn from the blade by turning handle B, until it is out of the path of oscillation of the blade, swinging on shaft C. The clamping member J is free to be removed as soon as the guard G is loosened. When the clamp J is removed and the guard G retracted as shown in Figs. 1, 2 and 3, the blade-holder and blade may be caused to oscillate by running the roller D back and forth over the surface of the strop or other sharpening implement. When the razor is moved in the direction of the straight arrow in Fig. 1, the rotation of the roller D, acting through pinions d and e, will swing the blade in the direction of the curved arrow, with its edge bearing at one side on the strop. So long as the razor is moved in the direction of the straight arrow the blade will be held by the frictional connection between the blade holder and the shaft, against the strop or hone at greater or less pressure according to the degree of such friction. As soon as the razor is moved in opposite directions on the strop or the like, the oscillating blade-holder and blade will swing into reverse position to sharpen the opposite side of the edge of the blade.

For convenience in manipulating the screws and in pushing the blade out of the blade-holder, the end of the hollow handle may be fitted with a removable cap b, to which is secured a slender rod b', adapted to be used either as a screw driver or a push rod to push the head f of the blade out of the grooves e.

I claim:

1. A safety razor, comprising a frame, a rotary shaft journaled in said frame, a blade-holder frictionally secured to said shaft, a blade removably mounted in said blade-holder, a roller adapted to rotate said shaft and oscillate said blade-holder and blade having its periphery projecting beyond the extremity of said frame, a guard engaging the inner side of said blade and movable out of the path of oscillation of said blade, and a detachable clamping member engaging the outer side of said blade.

2. A safety razor, comprising a forked frame, an oscillating blade-holder journaled between the forks of said frame, a blade removably mounted in said blade-holder, a roller adapted to actuate said blade-holder having its periphery projecting beyond the extremities of said fork, a guard having sliding connections with said fork engaging the inner side of said blade and movable out of the path of oscillation of said blade, and a clamping member engaging the outer side of said blade, detachably secured to said fork and held in position by the pressure exerted by said movable guard.

3. A safety razor, comprising a forked

frame, an oscillating blade-holder journaled 65 between the forks of said frame, a blade removably mounted in said blade-holder, a roller adapted to actuate said blade-holder having its periphery projecting beyond the extremities of said fork, a guard having 70 sliding connections with said fork engaging the inner side of said blade and movable out of the path of oscillation of said blade, a screw shaft actuated from the razor handle to move said guard, and a detachable clamp- 75 ing member engaging the outer side of said blade.

4. A safety razor, comprising a frame, an oscillating blade-holder journaled in said frame, a blade removably mounted in said 80 blade-holder, a roller adapted to actuate said blade-holder and blade, having its periphery projecting beyond the extremity of said frame, a guard engaging the inner side of 85 said blade and movable out of the path of oscillation of said blade, a detachable clamping member engaging the outer side of said blade and having a pair of inturned flanges, and a pair of lugs on said frame engaging the flanges of the clamping member and sup- 90 porting said member in position on the frame.

5. A safety razor, comprising a forked frame, an oscillating blade-holder journaled between the forks of said frame, a blade 95 removably mounted in said blade-holder, a roller adapted to actuate said blade holder and blade, having its periphery projecting beyond the extremities of said fork, frictional connections between said roller and blade-holder, a guard having sliding connections with said fork engaging the inner 100 side of said blade and movable out of the path of oscillation of said blade, a detachable clamp, engaging the outer side of said blade, and clamp engaging means on said 105 frame to support said clamp, said movable guard being adapted to coöperate with said clamp engaging means to bind the clamp in operative position with the blade between the clamp and guard.

6. A safety razor, comprising a frame, an oscillating blade-holder journaled in said frame, a blade removably mounted in said 110 blade-holder, a roller adapted to actuate said oscillating blade-holder and blade, having 115 its periphery projecting beyond the extremity of said frame, frictional connections between said roller and blade-holder, a guard engaging the inner side of said blade and movable out of the path of oscillation of the 120 blade, and a clamp engaging the outer side of said blade.

7. A safety razor, comprising a frame, an oscillating blade-holder journaled in said frame, a blade removably mounted in said 125 blade-holder, a roller adapted to actuate said oscillating blade-holder and blade, having its periphery projecting beyond the extremity

of said frame; frictional connections between said roller and blade-holder, means to vary the frictional engagement of said connections, a guard engaging the inner side of said 5 blade and movable out of the path of oscillation of the blade, and a clamp engaging the outer side of said blade.

Signed at Boston, Massachusetts, this 19th day of June 1914.
